UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

SELF-THREADING SHUTTLE.

Application filed August 11, 1919. Serial No. 316,547.

To all whom it may concern:

Be it known that I, JONAS NORTHRUP, a citizen of the United States, residing at Hopedale, in the county of Worcester and State of Massachusetts, have invented certain new and useful Improvements in Self- Threading Shuttles; and I do hereby declare the following to be a full, clear, and exact description of the invention, such as will enable others skilled in the art to which it appertains to make and use the same.

This invention relates to an improvement in self-threading shuttles for weft replenishing looms and more particularly to an improvement in thread blocks for such shuttles.

Self-threading shuttles as now constructed are usually provided with a longitudinal thread passage and with guiding means including a shield and beak by which the thread is guided during the threading operation into the delivery eye of the shuttle. In such self-threading shuttles it is highly desirable that the threading operation be completed as soon after replenishment as possible and in most of the self-threading shuttles now in use, the threading operation is usually completed during the first two picks of the shuttle after replenishment. In some instances, however, the irregularities in the course of the thread as it unwinds from the bobbin and passes over the top of the thread block during the first pick of the shuttle after replenishment prevent the thread from successfully passing under the shield and over the beak, the result being that the shuttle will not be threaded until the third and fourth picks thereof, instead of upon the first and second.

The object of the present invention is to provide a thread block for self-threading shuttles in which the course of the thread is so directed during the first portion of the threading operation as to insure passage of the thread under the shield and over the beak during the first pick of the shuttle after replenishment.

To this end a thread block is provided with a thread positioning device intermediate the guiding means and the bobbin which is arranged to engage the thread and control its course of movement from the bobbin to the guiding means so that it will pass through said guiding means during the first pick of the shuttle after replenishment.

With the above object in view, the invention consists in the thread block hereinafter described in the claims.

In the drawings illustrating the invention as embodied in a shuttle adapted for use in a right hand loom and with a right hand wind of bobbin, Figure 1 is a perspective of a portion of a shuttle showing the improved thread block; Fig. 2 a plan view; and Figs. 3 and 4 sections on lines 3—3 and 4—4 respectively of Fig. 2.

The self-threading shuttle illustrated in the drawings is described as follows: The shuttle body 10 is provided with the usual opening 11 for the reception of the bobbin or filling carrier 12. The shuttle body 10 is provided with a delivery eye 13 located in the front wall thereof, and the filling or thread is led from the bobbin 12 into and through the delivery eye 13 by the improved thread block, indicated generally by the reference character 14. The thread block 14 is received in a recess formed in the delivery end of the shuttle and is held therein by a threaded bolt 15 and nut 16. The thread block 14 is provided with the usual longitudinal thread passage 17 and with a shield 18, which overlaps a beak 19. A felt pad 20 is located at the inner end of the bottom of the longitudinal thread passage and serves to maintain an even tension on the thread. The construction and function of the parts thus far described are well known and form alone no part of the invention.

The thread block 14 is provided at the inner end with a thread positioning device 25 which is described as follows: The rear wall 27 of the longitudinal thread passage 17 is provided with a guide plate 26 which is curved downwardly and inwardly to near the inner end of the front wall 28 of the thread passage, and terminates in a downwardly and inwardly extended hook 30. A narrow inlet opening 29 is formed between the side of the hook 30 and the face of the front wall 28, through which the thread may pass around and under the hook 30. The portion of the plate 26 adjacent the rear wall of the thread passage 17 is extended downwardly in a substantially vertical direction to the bottom of the thread passage 17 and is provided with a second hook 35, extended transversely across the mouth thereof at a point below the first hook 30. The hook 35

- also forms an inlet 36 with the face of the front wall 28 of the thread passage 17 permitting the thread to pass around and below the hook 35. The upper surface of the hook 5 35 is substantially horizontal and forms a bearing surface upon which the thread may run during the initial portion of the threading operation, and the point of the hook 35 is extended forwardly.
- 10 The inner end of the top surface of the plate 26, in addition to being curved downwardly and forwardly toward the hook 30, also extends in a gradual outward curve from the top of the rear wall of the shuttle 15 body 10 toward the tip of the hook 30 thereby forming the flaring mouth 38 which tends to direct the filling into and through the inlet opening 29 and around and under the hook 30.
- 20 In operation, when a fresh bobbin is inserted in the shuttle after replenishment the thread extends from the bobbin diagonally across the thread block as indicated in Fig. 2, being fastened at its free end to the 25 hopper stud of the loom. After the lay starts on its backward beat the rearward movement of the shuttle with the lay causes the thread to be moved diagonally toward the flaring mouth 38 so that as the lay continues to beat back, the thread is moved directly into the mouth 38 and the natural 30 unwinding of the thread from the bobbin causes the same to enter and pass through the narrow inlet 29 around and under the 35 end of the hook 30 where it rests upon the upper surface of the lower hook 35. By this time the shuttle has started on its first pick and the thread being confined by the upper hook 30 at a point below the top of the inner 40 end of the thread block, its course of movement toward the shield and beak is so controlled that it readily passes under the shield and over the beak before the shuttle has completed its travel to the other side of the loom. 45 Upon the return pick of the shuttle, the thread is conducted in the usual way to the delivery eye and passes through the second inlet into the space below the second hook 35 in which position it continues during the 50 normal operation of the loom.
- The important features of the invention resides in the utilization of the relative movement of the thread across the shuttle when the lay starts to beat backward after 55 replenishment in order to assist in the threading operation of the shuttle and also in the provision of means for directing and controlling the course of the thread from the bobbin to the shield and beak during the 60 initial portion of the threading operation so that the passage of the thread under the shield and over the beak is insured during the first pick of the shuttle after replenishment.
- 65 Having thus described the preferred embodiment of the invention it will be understood that the same may be embodied in other forms within the scope of the following claims:
1. A thread block for self-threading shuttles having, in combination, a longitudinal thread passage, means for guiding the thread to the delivery eye of the shuttle, and a thread positioning device extended transversely of the mouth of the thread passage adapted to engage the thread upon the first rearward beat of the lay after replenishment and before the shuttle has started across the lay, and to control its course of movement from the bobbin to the 70 guiding means so as to insure passage of the thread between said guiding means on the first pick of the shuttle after replenishment.
2. A thread block for self-threading shuttles having, in combination, a longitudinal thread passage, means for guiding the thread to the delivery eye of the shuttle, and a thread positioning device at the inner end of the thread block in such position 75 with relation to the new filling thread as to engage it as the lay beats rearwardly and before it has reached a position to pass between said guiding means, and to thereafter control the course of its movements 80 to insure the passage of the thread between said guiding means on the first pick of the shuttle after replenishment, said thread positioning device comprising a plate extended inwardly and downwardly from one 85 wall of the thread passage transversely thereof to within a short distance of the inner end of the other wall of the thread passage and having its free end formed into a 90 depending hook.
3. A thread block for self-threading shuttles having, in combination, a longitudinal thread passage, means for guiding the thread to the delivery eye of the shuttle, means for maintaining the thread within 95 the thread passage during normal operation of the shuttle, and a positioning device extended transversely of the inner end of the thread passage and adapted to engage the new filling thread upon the first rearward 100 beat of the lay after replenishment in a manner to insure engagement of the thread by the said guiding means upon the first 105 pick of the shuttle.
4. A thread block for self-threading shuttles having, in combination, a longitudinal thread passage, means for guiding the thread to the delivery eye of the shuttle, a hook extended transversely of the inner 110 end of the thread passage to retain the thread within the passage, and a positioning device consisting of a hook extended across the top of the mouth of the thread passage 115 and having a substantially horizontal upper surface, said positioning device being 120
- Having thus described the preferred embodiment of the invention it will be understood that the same may be embodied in other forms within the scope of the following claims:
1. A thread block for self-threading shuttles having, in combination, a longitudinal thread passage, means for guiding the thread to the delivery eye of the shuttle, and a thread positioning device extended transversely of the mouth of the thread passage adapted to engage the thread upon the first rearward beat of the lay after replenishment and before the shuttle has started across the lay, and to control its course of movement from the bobbin to the 70 guiding means so as to insure passage of the thread between said guiding means on the first pick of the shuttle after replenishment.
2. A thread block for self-threading shuttles having, in combination, a longitudinal thread passage, means for guiding the thread to the delivery eye of the shuttle, and a thread positioning device at the inner end of the thread block in such position 75 with relation to the new filling thread as to engage it as the lay beats rearwardly and before it has reached a position to pass between said guiding means, and to thereafter control the course of its movements 80 to insure the passage of the thread between said guiding means on the first pick of the shuttle after replenishment, said thread positioning device comprising a plate extended inwardly and downwardly from one 85 wall of the thread passage transversely thereof to within a short distance of the inner end of the other wall of the thread passage and having its free end formed into a 90 depending hook.
3. A thread block for self-threading shuttles having, in combination, a longitudinal thread passage, means for guiding the thread to the delivery eye of the shuttle, means for maintaining the thread within 95 the thread passage during normal operation of the shuttle, and a positioning device extended transversely of the inner end of the thread passage and adapted to engage the new filling thread upon the first rearward 100 beat of the lay after replenishment in a manner to insure engagement of the thread by the said guiding means upon the first 105 pick of the shuttle.
4. A thread block for self-threading shuttles having, in combination, a longitudinal thread passage, means for guiding the thread to the delivery eye of the shuttle, a hook extended transversely of the inner 110 end of the thread passage to retain the thread within the passage, and a positioning device consisting of a hook extended across the top of the mouth of the thread passage 115 and having a substantially horizontal upper surface, said positioning device being 120

adapted to engage the thread upon the first rearward beat of the lay after replenishment to insure engagement of the thread by the guiding means upon the first pick of the shuttle.

5. A thread block for self-threading shuttles having, in combination, a longitudinal thread passage, means for guiding the thread to the delivery eye of the shuttle, 10 and a thread positioning device extended across the inner end of the thread passage and provided with a substantially horizontal upper surface, said positioning device being adapted to engage the new filling 15 thread upon the first rearward beat of the lay after replenishment and to thereafter hold the thread to insure passage of the

thread through the guiding means upon the first pick of the shuttle.

6. A thread block for self-threading 20 shuttles having, in combination a longitudinal thread passage, means for guiding the thread to the delivery eye of the shuttle, and a thread positioning device extended from the rear wall of the thread passage 25 across the inner end of the thread passage to the front wall thereof, said positioning device being adapted to engage the new filling thread upon the first rearward beat of the lay after replenishment and to thereafter hold the thread to insure passage of the thread through the guiding means upon the first pick of the shuttle.

JONAS NORTHRUP.
